UNITED STATES PATENT OFFICE.

JOHN H. STODDARD, OF RIDGEWOOD, NEW JERSEY.

FARE-INDICATING DEVICE AND SYSTEM.

Application filed October 29, 1925. Serial No. 65,544.

This invention relates to fare ticket apparatus and systems adapted for use in buses, trolley cars and other passenger vehicles in which a series of stacks of tickets for 5 different destinations and which are preferably of different colors or appearance may be mounted near the driver or conductor, so that he can in any suitable way tear or mark the tickets delivered to each passenger with 10 suitable stop indications showing the station or zone stop where the passenger entered the vehicle or paid his fare and also the amount of fare which should be paid. This may be effected conveniently by having a tearing cutter 15 movably mounted in connection with the stacks of tickets and any suitable actuating means may effect the relative movement between this cutter and the tickets. This cutter may, for example, be moved manually or 20 any desired automatic actuating means may be used which may include an actuating connection with the vehicle wheels so as to automatically move the tearing cutter down over the tickets in substantial proportion to the 25 distance traveled by the vehicle, or if desired, the actuating means may intermittently move the cutter with respect to the tickets. In many cases it is desirable to have the stacks of tickets locked or held in a suitable casing 30 in which the tickets are arranged with the corresponding stop indications on the different tickets in lateral or other alignment. This ticket casing may be locked or removably secured in or to a suitable support so as to 35 be replaceable by another casing and set of tickets at the end of the trip; or in some cases a duplex support may have a replaceable casing and a double set of tickets or a set of tickets and cooperating tearing cutter on 40 each of its opposite faces, and may be swivelingly or otherwise reversibly mounted on the vehicle so as to be merely turned upside down at the end of the route and then re-loaded with new ticket casings at the end of 45 the return trip of the vehicle. This system makes it possible to secure a ticket coupon or stub corresponding to each torn off ticket which is given to the entering passenger and at the end of the trip these coupons or stubs 50 may be removed and filed in connection with the conductor's report of the run, which gives a definite and convenient check on the fare receipts and passengers carried, etc.

In the drawings—

Fig. 1 is a front elevational view of a ticket holding device embodying this invention;

Fig. 2 is a cross-sectional view taken substantially along the line 2—2 of Fig. 1;

Fig. 3 is a sectional view through a stack of ticket stubs such as taken from the device of Fig. 1;

Fig. 4 illustrates a modified form of the invention, certain bearings and other parts being removed for simplicity of illustration;

Fig. 5 illustrates a form of ticket which may be used with the device of Fig. 4; and

Fig. 6 illustrates a further modification of the apparatus embodying this invention.

The device as illustrated in Figures 1 and 2 may comprise a supporting member 1 or 70 box-like structure having a back, two ends, and a bottom portion, but being open at its front and top sides. This supporting member is adapted to receive a ticket carrier or casing shown at 2. A tearing cutter carrier is 75 illustrated at 3, which cooperates with the support 1 in a manner hereinafter described. The ticket casing is provided with a front cover plate 4 which, with the parts in the position shown in Fig. 1 is largely covered by a 80 cutter or tearing member 5 mounted upon the carrier 3.

Tickets are provided at 6 and are secured in proper alignment by means of aligning pins 7, and being held upon such pins by the cover plate 4. A separate stack of tickets is provided for each destination along the route of the vehicle and each of the tickets is printed or otherwise provided with station or zone 85 stop indications arranged in succession along the ticket to indicate the various stations or stops from the beginning of the route to the particular destination represented by that ticket. For example, the first stack may comprise tickets from which portions may be torn for rides starting at any desired station or stop along the entire route, such rides terminating at the last stop on the route. The second stack of tickets may be similar to the first 90 except that the destination thereof may be the next to the last station or stop on the route. The third and succeeding stacks likewise correspond to the other destinations along the route. In this manner, the device may be 95 used to provide tickets between any two desired stations or zones. In the apparatus 100 105

shown the last stack of tickets may be used for local rides in any particular town or zone. To permit an inspector to readily check the sale of tickets and to avoid confusion by the operator or passengers, the stacks of tickets are preferably made of different colors or appearance. It will be understood that the passenger vehicle in most instances will have occasion to stop to take on passengers several 10 times within each fare zone. Accordingly the zone stop or station indications on the tickets above referred to are intended to indicate the successive zones and the proper fares for rides from such zones to other zones 15 regardless of the necessary number of stations or stops within each zone.

For operating the carrier 3 and its associated cutter or tearer member 5, a knob is provided at 8 and has a slotted shank 9 upon 20 which is fixed a toothed wheel 10. A pin 11 is received in the slotted shank and a washer 11' is retained in firm contact with the pin 11 by a coiled spring 12 embracing the shank and retained under compression between the 25 toothed wheel 10 and the washer 11'. The spring 12 serves to hold the toothed wheel 10 in engagement with suitable detents 13 formed on the adjacent surface of the carrier frame 3. The pin 11 is fixed upon a shaft 30 14 upon which shaft the shank 9 is also rotatably mounted. Pinions 15 are fixed upon the shaft 14 at each side of the ticket casing.

The shaft 14 may be rotatably mounted in suitable bearings forming a part of the carrier frame 3 and may be operated by the knob 8 when such knob is pulled to the right (as viewed in Fig. 1). In order to limit the rotation of the shaft 14 to one direction a suitable ratchet means may be provided as at 16. 35 Accordingly, when the knob 8 is pulled out, the shaft 14 may be rotated in a counter-clockwise direction (as viewed in Fig. 2), but cannot be rotated in the opposite direction. When the knob 8 is released, the shaft 40 is fixed against rotation by reason of the engagement of the toothed wheel 10 with the detents 13.

The pinions 15 are designed respectively to engage feeding rack members 17 and 18 45 fixed respectively to the two end portions of the support member 1. Upon turning the shaft 14 in the manner above described, the engagement of the pinions 15 with the rack portions causes the tearing carrier 3 to be gradually fed downwardly together with the tearer member 5.

The cover plate 4 may be attached to the ticket casing in any suitable manner as by a hinged portion 19 extending along the top 60 of the casing. The cover plate may be locked in the closed position as shown, to secure the ticket stubs against removal, by a suitable lock as indicated at 20 provided with a keyhole 21 and locking fins 22 which, when 65 in locked position, engage the outer face of

the cover plate 4. When the lock barrel is turned to the unlocked position, the fins are brought into a position directly over notches 23 cut in the cover plate 4 and the cover plate 4 may then be turned outwardly and upwardly since the fins 22 will freely pass through the notches. 70

The ticket casing 2 is designed to be replaceable as an assembled unit and is preferably introduced into the support 1 by sliding it downwardly therein. To lock the ticket casing against upward movement, a pin 25 is provided on the lock barrel 20 for engaging a suitable latch member 26 which is pivotally attached to the back of the support 1. 75 A suitable spring 24 normally retains the latch in the upright position shown. When the ticket casing is slid down into the support, the pin 25 pushes aside the latch 26 and when the ticket casing is in operative position, the latch snaps over the pin thus retaining the casing against sliding upwardly. However, upon rotating the lock barrel to unlocked position and in the direction indicated by the arrows in Fig. 1, the pin 25 will be rotated out of contact with the latch 26 and the pin will therefore no longer prevent removal of the ticket casing. 80

In order to retain the ticket casing 2 against movement toward the front of the support 1 suitable narrow flanges may be formed on each side of the support so as to project inwardly over the edges of the casing. Also if desired, light spring detents such as 27 on the cover 4 may be provided to engage elongated slots 28 formed in the sides of the support 1. As the ticket casing is slid into place, these spring detents 27 will slide down into the slots 28. These detents can be released by pushing them inwardly into released position when the casing is withdrawn from the support, thereby releasing the cover plate 4 which may thus be held down so as to keep the tickets in place even when the locking fins 22 are released. 100

As above stated, the cover plate 4 serves to hold the various stacks of tickets 6 upon the aligning pins 7. The cover plate 4 may be provided with suitable apertures 29 for receiving the aligning pins 7 and in this manner the ticket stubs are secured against slipping off the ends of the aligning pins. 105

However, the body portions of the tickets may be suitably perforated as at 30, or else formed of material which may be easily severed in order that the driver or conductor may quickly and easily remove the passengers' ticket portion without disturbing the remaining ticket stub. As the carrier 3 with the associated tearer member 5 is moved down over the face of the ticket casing, spring finger portions having tearing cutter edges as at 31 will successively engage the various portions of the tickets. The spring finger portions 31 should have sufficient flexibility and 110

strength to firmly engage the stack of tickets both before and after a substantial number of the tickets have been removed from any particular stack.

5 The ticket casing 2 is preferably divided into separate compartments for each stack of tickets by partition walls 32 and a wall 33 extending across the tops of the tickets.

10 The side frame portions at each end of the carrier 3 may be interconnected by a suitable carrier frame 34. The side frames may also be provided with suitable rollers 70 or other means for slidably engaging grooves 71 formed in the outer surfaces of the side walls 15 of the support 1 as indicated by the dotted lines in Fig. 2.

The device of Figures 1 and 2 may be operated as follows: Before a ticket casing is inserted in the support, the carrier frame 3 should be moved to its uppermost position as shown in Fig. 2. The stacks of tickets may be inserted in the ticket casing and the cover 4 locked thereon before the casing is inserted in the support. The casing with tickets may then be slid downwardly into the support, the locking pin 25 sliding freely within a slotted portion of the casing at 73 and into engagement with the latch 26. Simultaneously the spring detents 27 will enter the slot 28, and securely lock the casing in operative position. When the casing is thus in position, the carrier frame with its associated parts may be moved downwardly over the face of the ticket casing and tickets in substantial correspondence with the travel of the vehicle along the route. The tearing cutter edges 31 may be made to engage the tickets along the line adjacent the zone or station indications thereon corresponding to the location of the bus on the route. Accordingly, at any stop the vehicle operator may quickly sever the proper ticket by adjusting the carrier frame and by grasping the lower end of the desired ticket at slots as at 39 formed beneath each stack of tickets 45 at the lower side of the support 1. When the vehicle reaches the end of the route, the pinions 15 will be in engagement with the lower ends of the racks 17 and 18 and if desired the carrier frame may be drawn off the lower end of the support and out of the way to permit the ticket casing to be readily unlocked and removed. The non-return carrier frame, however, cannot be again replaced before the ticket casing is removed from the support since the ticket casing is provided with extensions 75 at its upper edge over which the carrier frame cannot pass. Accordingly, while the ticket casing is locked in the support, the carrier frame can only be moved downwardly and can neither be returned to the upper position nor replaced by a new carrier frame. Harmful tampering with the device by unauthorized persons is accordingly made very difficult. After the ticket casing has been removed, an inspector

or other authorized person can remove the remaining ticket stubs which may be filed away in groups as is indicated in Fig. 3 in connection if desired with the torn off passengers' tickets which are preferably collected when each passenger leaves the vehicle and are turned in by the driver at the end of his run. A pasteboard or other form of holder member 35 may be bent over at its top edge as at 36 to embrace a group of ticket stubs 37 as 70 taken from the dispensing device and may be securely retained thereon by a suitable paper clip 38. A permanent record is in this manner made available for checking the cash received for each run with the number and value 80 of tickets sold and the remaining ticket stubs.

If desired, automatic actuating means may be used to control the position of the carrier frame or ticket severing member. Such means may include an actuating connection with the vehicle wheels. For example, in the modification illustrated in Fig. 4 a ticket casing 41 cooperates with a severing member 42 for dispensing tickets 43. Suitable screw threaded feeding rods 44 and 45 may be provided at each side of the ticket casing for engaging corresponding threaded bearing members 46 at the ends of the severing member 42. The feeding rods may be suitably rotated by bevel gears at 47 and 48 respectively, which 90 are operated by a shaft and any suitable train of reduction gears at 49. A flexible drive shaft 50 of the form used for speedometers may be provided to operate the train of gears 49 by motive power furnished from the vehicle 100 wheels.

In Fig. 5 is illustrated a ticket designed especially for use with devices as of Fig. 4 where the severing means is controlled automatically in accordance with the movement of the vehicle. The spacing of the station or zone indications upon the tickets may in such cases vary in proportion to the distance between stations or zones on the vehicle route. Accordingly, a ticket 43 may be divided into several parts as at 53, 54 and 55 of various lengths corresponding to the length of ride in each zone or the distance between corresponding stations.

A modified form of device embodying the invention is illustrated in Fig. 6. In this device a carrier frame 58 is provided with a suitable severing member 59 having tearing cutter edges at 31 as in the device of Figures 1 and 2. In this device a special form of ticket casing 67 is provided and embraced by the carrier frame 58. The carrier frame may have a back portion 58' at the rear of the casing 67. To control the position of the carrier frame 58 in respect to the ticket casing, each side of the casing is preferably provided with ratchet teeth 60 to be engaged by a suitable actuator pawl 61, which is held in engagement with the ratchet teeth by a spring 62 and may be operated by the handle lever 63. To 115

prevent movement of the carrier frame while the handle 63 and its ratchet are being retracted, a suitable holding pawl 64 may be provided. The handle 63 may be pivotally mounted upon a shaft 65 supported from the carrier frame 58 and if desired provided at the other side of the casing with a similar lever arm and connected actuating pawl. Suitable tickets of the form described in connection with Fig. 1 are indicated at 6 and are received within an inner casing 66. The casing 67 may be provided with a tongue member as at 69 adapted to be received by the flanges of a supporting member 70. The supporting member 15 may be provided with suitable locking means 71 or other means to enable the device to be securely fixed to the vehicle.

It is not desired to limit the invention to the details or illustrative examples herein described and shown in a somewhat diagrammatic way in the drawings, since it will be obvious to those skilled in the art, after understanding the invention, that various other modifications and substitutions may be made 25 without departing from the scope of the invention, and I aim therefore, in the appended claims to cover all such modifications.

What is claimed as new and is desired to be secured by Letters Patent of the United 30 States is:

1. The fare ticket apparatus for passenger vehicles comprising a support, a replaceable ticket casing adapted to be locked in engagement with said support, a series of laterally arranged stacks of distinctively colored tickets for different destinations secured in said casing with the corresponding stop and fare indications in lateral alignment in the different stacks of tickets, a vertically movable tearing cutter mounted to cooperate with said casing and have its edge cooperate with the corresponding stop indications on all of said tickets, and non-return cutter actuating means for feeding said cutter down over said 45 tickets in substantial correspondence with the travel of the vehicle along its route for severing tickets having the proper stop and fare indications for each entering passenger and simultaneously leaving corresponding ticket stubs in said casing.

2. The fare ticket apparatus for passenger vehicles comprising a support, a replaceable ticket casing adapted to be locked in engagement with said support, a series of stacks of distinctively colored tickets for different destinations secured in said casing with the corresponding stop and fare indications in alignment in the different stacks of tickets, a movable tearing cutter mounted to cooperate with said casing and have its edge cooperate with the corresponding stop indications on all of said tickets, and actuating means for feeding said cutter over said tickets in substantial correspondence with the travel of the vehicle along its route for severing tickets having the

proper stop and fare indications for each entering passenger and simultaneously leaving corresponding ticket stubs in said casing.

3. Fare indicating means for passenger vehicles comprising a plurality of stacks of 70 tickets, a stack of tickets being provided for each destination on the route of the vehicle, zone or station indications being arranged in succession on each ticket to indicate the various zones or stations from the beginning 75 of the route to the particular destination indicated on that ticket, means for supporting and clamping the stacks of tickets in side by side arrangement with their corresponding station indications in predetermined relationship, and a ticket severing means for engaging the tickets at successive station indications as the vehicle proceeds along the route, whereby the operator may at each stop sever various tickets for rides from such 80 stopping point to any desired succeeding destinations on the route.

4. Fare indicating means for passenger vehicles comprising a plurality of stacks of 90 tickets, a stack of tickets being provided for each destination on the route of the vehicle, indications being arranged in succession on each ticket to indicate the various zones from the beginning of the route to the particular destination indicated on that ticket, means 95 for supporting and locking the stacks of tickets with their corresponding zone indications in predetermined relationship, and a ticket severing means for progressively engaging the tickets adjacent successive zone 100 indications as the vehicle proceeds along the route, whereby the operator may at each stop sever various tickets for rides from such stopping point to any desired succeeding destinations on the route.

5. Fare indicating means and ticket holding apparatus for passenger vehicles comprising a plurality of stacks of tickets, a stack of tickets being provided for each destination on the route of the vehicle, indications 110 being arranged in succession on each ticket to indicate the various zones from the beginning of the route to the particular destination indicated on that ticket, means for supporting and locking the stacks of tickets with 115 their corresponding zone indications in alignment, a ticket severing means, and non-return means for progressively advancing said severing means to cause engagement with the tickets at successive zone indications as the 120 vehicle proceeds along the route, whereby the operator may at each stop sever tickets for rides from such stopping point to any desired succeeding destinations on the route.

6. The fare ticket apparatus for passenger vehicles comprising a support, a replaceable ticket casing adapted to be locked in engagement with said support, a series of laterally arranged stacks of distinctively colored tickets for different destinations secured in 125

5 said casing with the corresponding stop and fare indications in alignment in the different stacks of tickets, a movable ticket severing means mounted to cooperate with said casing and to engage the corresponding stop indications on all of said tickets and for severing tickets having the proper stop and fare indications for each entering passenger and simultaneously leaving corresponding ticket stubs in said casing.

6 7. The fare ticket apparatus for passenger vehicles comprising a ticket casing, a series 15 of laterally arranged stacks of distinctively colored tickets for different destinations secured in said casing with the corresponding stop and fare indications in alignment in the different stacks of tickets and a movable tearing cutter mounted to cooperate with said casing and to engage the corresponding stop 20 indications on all of said tickets for severing tickets having the proper stop and fare indications for each entering passenger and simultaneously leaving corresponding ticket stubs in said casing.

25 8. Passenger travel or fare indicating means comprising a group of stacks of relatively long and narrow tickets, a stack of tickets being provided for each passenger destination on a route of travel, means at 30 one end of the stacks for securing the tickets of each stack together, indications being arranged in succession along the length of each ticket to indicate the various successive zone or station stops from the beginning of the 35 route to the particular destination indicated on that ticket, the indications for each particular station being at a predetermined position along the tickets and spaces being provided between said indications, said spaces 40 extending from side to side of each ticket, whereby ticket portions comprising the unsecured ends thereof may be readily severed at any zone or station stop along the route to indicate a ride to any remaining destination.

45 9. The combination of a ticket holder for supporting fare indicating tickets in position for convenient access, and a plurality of stacks of tickets, the tickets of each stack being alike but different from the tickets of the other stacks, a stack of tickets being provided corresponding to each destination along a route, each ticket bearing indications arranged in succession on the ticket to indicate 50 respectively the various zones from the beginning of the route to the particular destination indicated on that ticket, and means being provided on the holder for supporting and clamping the stacks of tickets in side-by-side arrangement with their corresponding zone 55 indications in predetermined relationship.

60 10. In combination a ticket holder support adapted for permanent attachment to a vehicle, a replaceable ticket holder provided

6 with means for locking the same in engagement with said support whereby fraudulent replacement is obviated, and a plurality of stacks of tickets, the tickets of each stack being alike but different from the tickets of the other stacks, a stack of tickets being provided corresponding to each destination along a route, each ticket bearing indications arranged in succession on the ticket to indicate 70 respectively the various zones from the beginning of the route to the particular destination indicated on that ticket, and means being provided on the holder for supporting and clamping the stacks of tickets in side-by-side arrangement with their corresponding zone 75 indications in predetermined relationship.

7. In combination a ticket holder support adapted for permanent attachment to a vehicle, a replaceable ticket holder provided with 80 means for locking the same in engagement with said support whereby fraudulent replacement is obviated, a plurality of stacks of tickets, the tickets of each stack being alike but different from the tickets of the other stacks, a stack of tickets being provided corresponding to each destination along a route, each ticket bearing indications arranged in succession on the ticket to indicate 85 respectively the various zones from the beginning of the route to the particular destination indicated on that ticket, and means being provided on the holder for supporting and clamping the stacks of tickets in side-by-side arrangement with their corresponding zone 90 indications in predetermined relationship.

8. In combination a ticket holder support adapted for permanent attachment to a vehicle, a replaceable ticket holder provided with means for locking the same in engagement with said support whereby fraudulent replacement is obviated, a plurality of stacks of tickets, the tickets of each stack being alike but different from the tickets of the other stacks, a stack of tickets being provided corresponding to each destination along a route, each ticket bearing indications arranged in succession on the ticket to indicate 95 respectively the various zones from the beginning of the route to the particular destination indicated on that ticket, means being provided on the holder for supporting and clamping the stacks of tickets in side-by-side arrangement with their corresponding zone 100 indications in predetermined relationship, and means for locking the tickets within the replaceable holder whereby fraudulent replacement of tickets is obviated while the holder is locked in the support.

9. The combination of a ticket holder for supporting fare indicating tickets in position for convenient access, and a plurality of stacks of tickets, the tickets of each stack being substantially alike but different from the tickets of other stacks, the tickets of the different stacks respectively being representative of rides of different maximum lengths, each ticket bearing a plurality of zone 110 indications arranged in succession on the ticket, and means being provided on the holder for supporting and clamping the stacks of tickets in side-by-side arrangement with their corresponding zone 115 indications in predetermined relationship.

10. The combination of a ticket holder for supporting fare indicating tickets in position for convenient access, and a plurality of stacks of tickets, the tickets of each stack being substantially alike but different from the tickets of other stacks, the tickets of the different stacks respectively being representative of rides of different maximum values, each ticket bearing a plurality of zone 120 indications arranged in succession on the ticket,

- means being provided on the holder for supporting and clamping the stacks of tickets in side-by-side arrangement with their corresponding zone indications in predetermined relationship, and movable ticket tearer means mounted on said holder having tearer members individual to each of said stacks of tickets and cooperating with the zone indications thereon, whereby the operator may advance the tearer means as the vehicle proceeds on the route to bring said tearer members into engagement successively with the zone indications corresponding to the progress of the vehicle on the route, permitting the tearing of a ticket from any of the stacks to provide passenger ticket portions and stub portions both torn to indicate the zone in which the passenger came aboard.
14. Fare ticket apparatus for passenger vehicles comprising a ticket casing in combination with a series of laterally arranged distinctive stacks of tickets respectively representative of rides of various values, said tickets having fare and zone indications thereon and said stacks of tickets being secured in said casing with the corresponding zone indications in predetermined relationship, and movable tearing cutter means mounted to cooperate with said casing and to engage the corresponding zone indications on the tickets of each of said stacks for severing tickets having the proper zone and fare indications for each entering passenger and simultaneously leaving corresponding ticket stubs in said casing.
15. Fare ticket apparatus for passenger vehicles comprising a ticket casing in combination with a series of laterally arranged distinctive stacks of tickets respectively representative of rides of various values, each of said tickets having a series of zone indications thereon and said stacks of tickets being secured in said casing with the corresponding zone indications on the tickets of the several stacks in predetermined relationship, movable tearing cutter means mounted on said casing and having portions individual to each of said stacks of tickets and cooperating with the zone indications thereon for severing tickets of the proper value to represent the desired ride of each entering passenger and torn to indicate both on the stub and passengers' portions the zone in which the passenger came aboard.
16. The combination of a ticket holder for supporting fare indicating tickets in position for convenient access, and a plurality

of stacks of tickets, the tickets of each stack being substantially alike but different from the tickets of other stacks, each ticket being provided with fare indications and a plurality of zone indications, the corresponding zone indications on all the tickets being arranged in a predetermined relationship, and movable ticket tearer means mounted on said holder having tearer portions individual to each of said stacks of tickets and cooperating with the zone indications thereon to engage corresponding zone indications on the tickets of all of said stacks for severing tickets having the proper value and zone indication for each entering passenger, means being provided on the holder for supporting and clamping the stacks of tickets in side-by-side relationship and for concealing the stub portions.

17. Fare ticket apparatus for passenger vehicles comprising a ticket casing in combination with a series of laterally arranged distinctive stacks of tickets respectively representative of rides of various values, each of said tickets having a series of zone indications thereon and said stacks of tickets being secured in said casing with the corresponding zone indications on the tickets of the several stacks in predetermined relationship, movable tearing cutter means mounted on said casing and having portions individual to each of said stacks of tickets and cooperating with the zone indications thereon for severing tickets of the proper value to represent the desired ride of each entering passenger and torn to indicate both on the stub and passengers' portions the zone in which the passenger came aboard.

18. Fare ticket apparatus for passenger vehicles comprising a ticket casing in combination with a series of laterally arranged distinctive stacks of tickets respectively representative of rides of various values, each of said tickets having a series of zone indications thereon and said stacks of tickets being secured in said casing with the corresponding zone indications on the tickets of the several stacks in predetermined relationship, movable tearing cutter means mounted on said casing and having portions individual to each of said stacks of tickets and cooperating with the zone indications thereon for severing tickets of the proper value to represent the desired ride of each entering passenger and torn to indicate the zone in which the passenger came aboard, and a manually rotatable member for controlling the position of said individual tearer portions.

In testimony whereof I have signed my name to this specification.

JOHN H. STODDARD.
